PALLET

William D. McIntyre, Monroe, Mich., assignor to
 Monroe Auto Equipment Company, Monroe,
 Mich., a corporation of Michigan

Application August 21, 1946, Serial No. 692,028

3 Claims. (CL. 248—120)

1

This invention relates generally to material handling equipment and refers more particularly to improvements in load supporting pallets.

One of the objects of this invention is to greatly simplify the construction of pallets and thereby materially reduce the cost of manufacture thereof.

Another object of this invention is to provide a pallet comprising complementary vertically spaced sheet metal plates capable of being produced by relatively simple stamping operations with embossed portions which cooperate to form vertical load supporting columns or spacers between the plates.

A further object of this invention is to provide a pallet of the above general type wherein the number and spacing of the columns or spacers is predetermined to not only adequately support high unit loads, but to also provide entry slots at all sides and corners of the pallet for receiving the fork of a suitable truck. Thus the pallet may be set down from one direction and picked up from another with the result that removal of unit loads need not necessarily be a reversal of the load placement process, and aisle space required for manipulating the loads may be reduced to a minimum.

A further object of this invention is to provide a pallet wherein the vertical spacing or load supporting columns are formed of sections respectively stamped from the plates and permanently secured together.

A still further object of this invention is to provide spaced registering areas of the plates with groups of tongues projecting toward one another with the tongues in the respective groups symmetrically arranged with respect to a common point and with the tongues on one plate permanently secured to the tongues on the other plate to form a plurality of spaced load supporting columns between the plates.

The foregoing as well as other objects will be made more apparent as this description proceeds, especially when considered in connection with the accompanying drawing, wherein:

Figure 1 is a plan view of a pallet constructed in accordance with this invention;

Figure 2 is a side elevational view of the pallet shown in Figure 1;

Figure 3 is a sectional view taken on the plane indicated by the line 3—3 of Figure 1;

Figure 4 is a plan view of a modified pallet construction;

Figure 5 is a side elevational view of the pallet shown in Figure 4;

Figure 6 is a sectional view taken on the plane indicated by the line 6—6 of Figure 4; and

Figure 7 is a fragmentary plan view showing one step in the method of manufacturing the pallet shown in Figure 4.

The pallet shown in Figures 1 to 3 inclusive of the drawings comprises two plates 10 and 11 secured in vertical spaced relation by load sustaining columns 12. The plates are formed of sheet metal and, in the interests of economy of manufacture, are designed to enable producing the same by a simple stamping operation. It will also be noted that the two plates are complementary or identical in construction, so that the same die and press may be employed to produce both plates. This not only reduces the equipment required to produce the pallet to a minimum, but in addition, greatly simplifies assembly.

With the above in view, reference is now made more in detail to the construction of the pallet shown in the drawings, wherein it will be noted that the bottom or base plate 10 is embossed at laterally spaced areas to provide buttons 13 having frustro-conical side walls and having end walls 14 lying in a common plane parallel to the plane of the plate. As previously stated the top plate 11 is identical to the bottom of base plate 10 and corresponding parts are indicated by the same reference numerals.

In assembly the top plate 11 is superposed on the base plate 10 in an inverted position with respect to the latter and with the end wall 14 of the buttons engaging each other. These end walls are welded or otherwise permanently secured together so that the buttons 13 on the respective plates cooperate to form the vertical load sustaining columns 12.

The length of the columns 12 is predetermined to space the plates apart a distance sufficient to enable the fork on the usual pick-up truck to be readily inserted between the plates. In this connection it will also be noted that while a sufficient number of columns is provided to assure supporting the required loads without buckling the plates, nevertheless, the columns are arranged to enable inserting the truck fork between the plates at either of the four sides of the pallet or at either of the four corners. This feature greatly enhances maneuverability in confined spaces and assures obtaining maximum storage arrangements.

The pallet shown in Figures 4 to 7 inclusive comprises a rectangular shaped bottom or base plate 15, a correspondingly shaped top plate 16, and vertical columns 17 between the plates. The number of vertical columns 17 and the spacing between the columns is predetermined to transfer stresses resulting from supporting extremely heavy loads on the top plate 16 to the bottom plate 15 without buckling the top plate 16. Regardless of the number of columns 17 provided between the plates, these columns are arranged to enable the usual load lifting fork of a conventional transfer truck to be readily inserted between the plates at either of the various sides

of the pallet or at either of the four corners of the pallet. Such an arrangement facilitates manipulation of the pallets by the transfer truck and affords a wide variety of stowage arrangements.

Both plates of the pallet are preferably formed of sheet metal and are designed to enable fabricating the same by simple, inexpensive stamping operations. As shown particularly in Figure 6 of the drawings, each column 17 is formed of two sections 18 and 19 respectively formed integral with the plates 15 and 16.

The section 18 of each column 17 comprises a plurality of triangular shaped tongues 20 struck upwardly from the base plate 15 and symmetrically arranged with respect to a common point. The tongues 20 project upwardly from the plate 15 in converging relationship, and the upper ends of the tongues are bent laterally inwardly to form flanges 21 having the top surfaces lying in a common plane parallel to the plane of the plate 15.

In Figure 7 of the drawings, one simple and inexpensive method for forming the tongues 20 is shown. The sheet metal plate 15 is sheared along lines 22 which intersect one another at substantially right angles to provide triangular portions 23. The triangular portions are bent at right angles to the plane of the plate 15 about the lines 24 to provide the tongues 20, and the extremities of the triangular portions are bent laterally inwardly along the lines 25 to form the flanges 21.

The column sections 19 depending from the top plate 16 are preferably formed in the same manner as the sections 18 to provide triangular shaped tongues 26 having inwardly extending flanges 27 at the free ends thereof. The two plates are positioned in superposed relation, with the sections 18 and 19 in registration. As a result, the flanges 21 on the tongues 20 assume positions directly opposite the flanges 27 on the tongues 26. In the present instance a rectangular plate 28 is interposed between each of the column sections 18 in such a position that the corners of the plate extend between the flanges 21 and 27 on the respective tongues. The tongues 21 and 27 are welded or otherwise permanently secured to the plates 28 to thereby integrally connect the base plate 15 of the pallet to the top plate 16. The intermediate plates 28 not only serve as an anchorage means between the column sections, but also function to effectively reinforce the columns. If desired the base and top plates of the pallet may be reinforced by providing upstanding ribs 29 at the marginal edges thereof. In the present instance, the ribs 29 are formed by return bending the marginal edges of the bottom and top plates in the manner clearly shown in Figure 6 of the drawings.

What I claim as my invention is:

1. A pallet comprising a base plate, a plurality of spaced groups of integral load-supporting projections formed in and struck from said base plate, each of said groups including a plurality of oppositely disposed projections of a triangular shape in plan view with their sides converging

toward a common point, said projections being bent upwardly away from the plane of said base plate so that the free ends thereof are disposed in a spaced relationship relative to each other, a top plate having correspondingly formed and spaced projections extending downwardly away from the plane thereof, and means interconnecting the free ends of the projections of the top and base plates to provide load-supporting columns between said plates.

2. A pallet comprising a base plate, a plurality of spaced groups of integral load-supporting projections formed in and struck from said base plate, each of said groups including a plurality of oppositely disposed projections of a triangular shape in plan view with their sides converging toward a common point, said projections being bent upwardly away from the plane of said base plate so that the free ends thereof are disposed in a spaced relationship relative to each other, the free ends of said projections being bent laterally to form flanges lying in a plane parallel to the plane of the base plate, a top plate having correspondingly formed and spaced projections extending downwardly away from the plane of said top plate, the free ends of said top plate projections being bent laterally to form flanges lying in a plane parallel to the plane of said top plate, and means interconnecting the flanges on the free ends of the projections of the top and base plates to provide load-supporting columns between said plates.

3. A pallet comprising a base plate, a plurality of spaced groups of integral load-supporting projections formed in and struck from said base plate, each of said groups including a plurality of oppositely disposed projections of a triangular shape in plan view with their sides converging toward a common point, said projections being bent upwardly away from the plane of said base plate so that the free ends thereof are disposed in a spaced relationship relative to each other, the free ends of said projections being bent laterally to form flanges lying in a plane parallel to the plane of the base plate, a top plate having correspondingly formed and spaced projections extending downwardly away from the plane of said top plate, the free ends of said top plate projections being bent laterally to form flanges lying in a plane parallel to the plane of said top plate, and a plate supported between the flanges of the top and base plate projections and secured thereto.
